ELECTRIC FUSE

Original Filed May 7, 1919

INVENTOR. HENRY T. BUSSMANN

ATTORNEY

Roy Weiss

UNITED STATES PATENT OFFICE.

HENRY T. BUSSMANN, OF ST. LOUIS, MISSOURI.

ELECTRIC FUSE.

Original application filed May 7, 1919, Serial No. 295,372. Divided and this application filed January 17, 1922. Serial No. 529,968.

This application is a division of application Serial No. 295,372 filed May 7, 1919.

My invention relates to electric fuse links and the object of my invention is to provide a fuse link that will operate satisfactorily under any conditions.

In the drawings, Fig. 1 shows a view of my improved fuse link and Fig. 2 an elevational view thereof. Fig. 3 shows a detailed view.

The fuse link has its center portion covered with insulating material 7. This serves to conduct the heat away from that portion of the strip and causes the strip to blow at the narrow uncovered portions 4, allowing the center section to drop out and break the arc. Where it is desired to have the strip burn out at more than two points, additional independent sections of insulating material are placed on the center portion.

On the blowing of fuse links an arc continues which burns back on the terminal portions of the link. These terminal portions being of greater width than the active portion of the strip, it can be seen that the amount of metal vaporized is very considerably increased because of this action.

I overcome this by providing a hard, tenacious, closely adhering insulating material 5 to act as an arc shield on the terminal portions 6, in addition to the insulated section or sections on the center portion, so that when the fuse is blown and the center portion or portions drop out, that the arc will be quickly extinguished.

I have also found that by using a hard,

tenacious adhering material, preferably moulded mica, or bakelite, condensite, or like materials, placed or compressed on the center portion, that I can obtain better results than with other materials that have been used heretofore, as this material will, in addition to conducting the heat away from that portion of the strip, act as an effective arc shield by reason of its being able to withstand the high heat and explosive effect of the arc.

What I claim is:

1. A fuse link having an area of reduced cross section and an area of enlarged cross section and an arc shield protecting that surface of the enlarged cross section facing the area of reduced cross section. 50

2. A fuse link having terminal areas and an area of reduced cross section intermediate the terminal portions and an insulating material protecting that surface of the terminal portions facing the reduced cross section. 55

3. A fuse link having a plurality of readily fusible portions and an area of enlarged cross section and an arc shield protecting a portion of the surface of the enlarged cross section facing the readily fusible portions. 65

4. A fuse link having an area of reduced cross section and an enlarged portion contiguous thereto and an insulating material covering the narrow surface of the enlarged portion abutting on and facing the reduced area. 70

HENRY T. BUSSMANN.
